UNITED STATES PATENT OFFICE.

JOHN E. THRON, OF PHILADELPHIA, PENNSYLVANIA.

OILER.

No. 897,561.

Specification of Letters Patent.

Patented Sept. 1, 1908.

Application filed October 21, 1907. Serial No. 398,343.

To all whom it may concern:

Be it known that I, JOHN E. THRON, a citizen of the United States, residing at Philadelphia, in the county of Philadelphia and 5 State of Pennsylvania, have invented certain new and useful Improvements in Oilers, of which the following is a specification.

This invention relates to oilers and particularly to that class used in lubricating shafts, 10 bearings and other mechanical parts not readily accessible from the surface on which the operator may be positioned.

The objects of this invention are, to provide an oiler capable of reaching, either vertically 15 or angularly, to a considerable distance beyond the ordinary scope or reach of the operator, thereby doing away with the use of ladders and other contrivances of similar purpose.

20 A second object is, to provide such oilers adapted to be used with entire readiness by even inexperienced persons. Third, to provide such devices in forms economical to manufacture and which shall effectually fulfill their functions.

These and other minor objects are attained by the novel combination and arrangement of parts, hereinafter described and shown in the accompanying drawings, in which:—

30 Figure 1, represents a side elevation of the entire device, a portion of the same being broken away in order to show the interior arrangement. Fig. 2, is a transverse section of the same taken on a line indicated by 35 the characters *a—a*, of Fig. 1. Fig. 3, is a transverse section of the handle taken on a line indicated by the characters *b—b*, of Fig. 1.

The device consists of a cylindrical reservoir 1, preferably made from a suitable section of tube, threaded for the cover 2, which is provided at the extreme upper end with a cap 3; the lower end of the tube is similarly threaded and attached to a light metal frame 4, having immediately above the threads a 45 circular portion provided with posts 5, which support a similar portion 6, which forms the bottom of the oil chamber.

In the center of the portion 6, is an annular projection 7, to which is tightly fitted a 50 tube 8, forming the chamber of a pump and containing therein a piston 9; this piston is operated by means of the piston-rod 10, secured in any suitable manner to it; about the rod and within the chamber is disposed an 55 openly wound helical spring 11, in such manner as to exert its tension against the lower

side of the piston keeping it normally extended.

Near the bottom of the pump chamber 8, is an opening 12, provided with a clapper 60 valve 13, the same being so arranged that as the piston ascends oil is drawn in to the pump chamber through the opening 12, but on the return stroke of the piston it is prevented from flowing back into the outer cylinder, 65 but caused to pass through the orifice 14, of the chamber 15, which has connected therewith the discharge pipe or oiler spout 16, secured as at 17, to the chamber casing, and curved or turned downward as may be desired at 18, in order that the oil may be discharged at any given point.

The piston-rod 10 passes freely through the frame 4, and stuffing box 19, where it connects with a cord or wire 20.

75 At the lower part of the frame 4, are secured Y shaped members 21, united in a ferrule 22, which is adapted to receive the handle 23, of any length suitable for the purpose to which the oiler may be applied; this handle may be preferably circular in cross section and contains a slot-way 24, through which the cord 20 passes, it being attached at its extreme lower end to the hook shaped catch 25, which fits freely within the recess 85 24, and is adapted to be grasped by the operator in manipulating the oiler.

The catch is kept in its proper relative position by means of the guide pins 26 and 26', which also limit the movement which may 90 be given to it laterally.

In operation the cap is removed and the reservoir filled with oil, or other desired fluid, and the cap replaced, whereupon the oiler is in condition for operation; a downward pull 95 of the hook catch 25, is transmitted through the cord to the piston-rod and piston, causing the latter to descend and force any liquid that may be contained in the pump chamber through the opening 14, and hence through 100 the spout to its point 18; upon releasing the hook 25, it is carried upward by the spring 11, which has the effect of raising the piston as well and replenishing or recharging the pump chamber 8.

105 It will be obvious that minor changes may be made in the design and construction of the oiler without departing from the spirit of the invention or the scope of the claims.

Having thus described my invention what 110 I claim as new and desire to secure by Letters Patent is:

1. An oiler comprising a reservoir having a discharge pipe, a pump cylinder disposed within the reservoir, a piston within the pump cylinder, a clapper valve arranged at 5 the lower end and in the walls of the said cylinder, a frame connecting the cylinder and the reservoir at the lower end thereof, a piston-rod, a stuffing box connected with the frame, a handle of indeterminate length attached to the frame, an operating hook and connecting means between said hook and said piston rod, all substantially as shown and described.
2. In combination with an oiler comprising 15 a cylindrical casing, a discharge pipe connected therewith, a pump within the casing and operative means combined therewith, of a frame partly below and within said casing, said frame having a chamber communicat-
- ing with the said pump, and a handle of indefinite length, all substantially shown and described. 20
3. In an oiler of the class described, the combination with a casing and pump therein, of an integral hollow frame having communicating passages between the pump and discharge outlet, said frame forming the connecting means between the casing and its handle, all substantially as shown and described. 25

In testimony whereof I have signed my name to this specification in the presence of two subscribing witnesses.

JOHN E. THRON.
